SPOOL HOLDER

Louise C. Hogan, Spokane, Wash.

Application April 16, 1934, Serial No. 720,794
Renewed November 25, 1935

1 Claim. (Cl. 242—134)

My invention relates to spool holders and more particularly to spring holders that may be installed in combination with a sewing case, basket, drawer or display case for the purpose of holding spools, pin cushions, thimbles and the like. The principal objects of the invention are to provide simple spring devices that may be connected to a sewing or other receptacle, and upon which spools and other articles used in sewing may be installed or removed by a single movement of the hand. Other objects are to provide a ready and convenient means for holding sewing articles and which may be manufactured at very small cost. With the above and other objects in view which will appear as the description proceeds, the invention consists of the novel construction, adaptation, combination and arrangement hereinafter described and claimed. These objects are accomplished by the devices illustrated in the accompanying drawing; wherein:—

Figure 1 is a view in perspective showing a number of the holders connected to the interior of a sewing case with spools and other sewing articles installed thereon; Fig. 2 is a detail view in vertical section through one of the spools and taken on a broken line 2—2 of Fig. 1; Fig. 3 is a detail view in perspective showing the type of holder that is used for spools or other hollow articles; Fig. 4 is a detail view in perspective showing the form of holder that retains the articles by outside pressure; Fig. 5 is a vertical section of the holder of Fig. 4.

Referring to the drawing throughout which like reference numerals indicate like parts, the numeral 5 designates a receptacle or case of any form wherein sewing equipment is kept or displayed. Connected to the interior of said receptacle are a plurality of holders which will now be described in detail.

The holder which is most commonly used, and which is shown in Figs. 2 and 3 of the drawing, consists of an upright arm 6 which is bent downwardly upon itself to form a bulging arm 7. The lower portion of said bulging arm is formed into a loop 8 which encircles the lower portion of the upright arm 6. The lower end of said upright arm is pointed and threaded at 9 to provide means whereby the holder may be fastened to the receptacle 5, although it will be understood that any other fastening may be used.

Referring particularly to Fig. 2 of the drawing, in the use of this form of holder, its lower threaded end 9 is screwed or otherwise fastened to the receptacle 5. A spool or other object having a hole 10 therethrough is installed on the holder by placing the spool thereon with the arms

6 and 7 projecting into said hole. The holder is made of spring wire, and the outward pressure of said arms against the interior surface of the hole retains the spool in place regardless of the position of the holder. The spool may, of course, be removed by simply lifting or pulling it off the holder, and it will thus be seen that the spool may be installed or removed by one movement of the hand, thus providing a very convenient and ready means for holding spools and the like. 10

The form of holder shown in Figs. 4 and 5 comprises a plurality of horizontal arms 11 radiating from a common center and having depending spring portions 12 joining a central depending pointed and threaded portion 13 by means of 15 which the holder is fastened into the receptacle 5 or other surface. The outer ends of the arms 11 are formed into loops 14 which engage the outer surface of articles installed therein as shown in Fig. 5. I will also be understood that 20 said loops may engage the inner surface of a thimble or other hollow article as shown in dotted lines in Fig. 1.

In the use of the form shown in Figs. 4 and 5, the spools and other objects are installed or removed by a single movement. This form may be used in displaying spools of thread and other articles in a show case or the like. The advantage in using this form for displaying spools is that the paper label on each end of the spool is 30 unbroken in its use.

It will now be apparent that I have provided a very simple, handy and ready means for holding or displaying spools and other articles used in sewing. Having thus described my invention, 35 what I claim and desire to secure by Letters Patent of the United States is:—

A spool holder consisting of a strand of resilient wire bent back upon itself intermediate its length to form a standard and an arm spaced transversely from the standard and having one end integrally united with the adjoining end of the standard by an arcuate portion, the other end of the standard being formed with a support engaging portion, said arm being bowed outwardly 45 and having its other end portion bent to form an inwardly extending loop loosely engaged about the standard adjacent the support engaging portion thereof and constituting an abutment for engaging an end face of a spool and limiting 50 movement of the arm and standard through the bore of a spool thrust upon the holder and held thereon by frictional grip of the arm and standard.

LOUISE C. HOGAN. 55
